CLAIM

The ornamental design for a cleaning product dispenser, as
shown and described.

DESCRIPTION

FIG. 1 is a perspective view showing our new design for a cleaning product dispenser;
FIG. 2 is a front view of the embodiment of FIG. 1;
FIG. 3 is a back view of the embodiment of FIG. 1;
FIG. 4 is a right side view of the embodiment of FIG. 1;
FIG. 5 is a left side view of the embodiment of FIG. 1;
FIG. 6 is a top view of the embodiment of FIG. 1;
FIG. 7 is a bottom view of the embodiment of FIG. 1;
FIG. 8 is a perspective view showing a second embodiment
of our new design for a cleaning product dispenser;
FIG. 9 is a front view of the embodiment of FIG. 8;
FIG. 10 is a back view of the embodiment of FIG. 8;
FIG. 11 is a right side view of the embodiment of FIG. 8;
FIG. 12 is a left side view of the embodiment of FIG. 8;
FIG. 13 is a top view of the embodiment of FIG. 8; and,
FIG. 14 is a bottom view of the embodiment of FIG. 8.
In the figures, the broken lines represent unclaimed subject
matter and form no part of the claim.
